UNITED STATES PATENT OFFICE.

JESSE BECHT, OF CONNERSVILLE, INDIANA.

FENCE JACK.

Application filed June 27, 1927. Serial No. 201,797.

The present invention is directed to improvements in fence jacks.

The primary object of the invention is to provide a device of this character so constructed that the line wires of a fence can be drawn downwardly for securement to the fence post embedded upon the sides of a shallow ravine or ditch.

Another object of the invention is to provide a device of this character which can be conveniently attached to the line wires of a fence and anchored and is capable of manipulation to simultaneously adjust the line wires of the fence in order that they can be properly positioned with respect to the fence posts for attachment thereto.

In the accompanying drawings:

Figure 1 is a perspective view of the jack showing the same in use upon a fence.

Figure 2 is a side elevation of the device.

Figure 3 is a fragmentary rear elevation of the wire adjusting bar.

Figure 4 is a sectional view on line 4—4 of Figure 3.

Figure 5 is an enlarged view of the jack, showing one of the side plates removed.

Figure 6 is a sectional view on line 6—6 of Figure 2.

Figure 7 is a detail sectional view of the lock bolt casing.

Figure 8 is a vertical sectional view through the lock bolt casing.

The jack comprises a head 1 which consists of a pair of side plates 2, the forward edges of which are provided with ribs 3, said plates being held together by bolts 4. Bolted between the lower ends of the plates 2 is a block 5 which carries a casing 6 in which is mounted a lock bolt 7, the inner end of the rod 8 being secured thereto, there being a coil spring 9 encircling the rod and bearing against the bolt to urge the same outwardly, said rod having a ring 10 carried by its outer end which may be grasped for drawing the bolt fully within the casing.

A line wire engaging bar 11 is employed and has its forward edge provided with a plurality of wire engaging notches 12, the rear edge of said bar being clamped between a pair of strips 13, the space between the strips being bridged by a plurality of pins 14, constituting teeth, the purpose of which will later appear.

55 A lever 15 is pivotally mounted between

the plates 2 upon a pin 16 supported by said plates, and having pivotal connection with said pin is a pawl 17, there being a coil spring 18 having one end connected to the pawl adjacent its pivotal point and its other end connected intermediate the ends of the lever.

To the pawl is fixed a handle 19 to facilitate the disengagement of the bill 20 of the pawl from the pins or teeth 14.

A yoke 21 is pivoted to the head 1 and has a hook 22 carried thereby and to which the upper end of a chain 23 is attached, the lower end of the chain being adapted to be fastened to an anchor block 24 which serves to hold the head 1 against upward movement when the lever 15 is being rocked for feeding the bar 11.

As shown in Figure 1 the fence posts 25 are located upon the opposite sides of a shallow ravine or ditch and it is necessary that the line wires 26 be drawn downwardly for securement to the posts, and in order to accomplish this the line wires are engaged in the notches 12 of the bar 11. The lever 15 is rocked upwardly and since the head 1 is anchored to the block 24 the head will remain stationary, but the bar 11 will move downwardly since the pawl 17 is engaged with one of the pins or teeth 14. The bolt 7 is withdrawn from engagement with the teeth 14 and as the lever is swung upwardly the bar 11 will move downwardly until the wires 26 are properly positioned upon the posts for securement thereto. The bolt is then released to engage a tooth to hold the heads while the pawl is adjusted by the handle for engagement with another tooth, the spring 18 serving to hold the bill 20 of the pawl positively engaged with the teeth.

It will be of course obvious that in cases where the fence is built over ridges or high points of ground that the chain 23 may be engaged with one of the posts and upon reversing the position of the jack the wires may be moved upwardly instead of downwardly, as shown.

Having thus described the invention, I claim:

1. A jack of the class described comprising a head, a lever pivoted to the head, a fence wire engaging bar slidably associated with the head, a pawl pivoted to the lever for engagement with the bar to slide the same relative to the head and a latch bolt asso-

105

110

ciated with the head for engagement with the bar to hold the same in adjusted positions with respect to the head.

2. A jack of the class described, comprising a head, a lever pivotally supported by the head, a pawl pivoted to the lever, a fence wire engaging bar slidably associated with the head and having teeth thereon for engagement with the pawl, a latch bar slidably supported by the head for engagement with the teeth, said pawl serving to move the bar relative to the head upon operation of the lever, said latch bar being adapted to engage the teeth of said bar to hold the same in fixed adjustment with respect to the head, and a handle carried by the pawl for disengaging the same from the teeth.

3. A jack of the class described comprising a head, a casing supported by the head, a spring pressed latch bolt slidable in the head, a lever pivotally connected to the head and having a pawl pivotally connected thereto, a fence-wire engaging bar including a plurality of teeth for engagement with the pawl for sliding the bar relative to the head, a handle carried by the pawl for disengaging the same from the teeth carried by the bar,

said latch being adapted to engage the teeth to maintain the bar in fixed adjustment relative to the head, and a spring connecting the pawl and lever for maintaining the pawl yieldably engaged with the teeth.

4. A jack of the class described comprising a head, a lever pivotally connected to the head and having a pawl pivotally connected thereto, a bar including a pair of strips, a fence wire engaging bar engaged between the strips, said strips having pins carried thereby and constituting teeth for engagement with the pawl, a casing carried by the head and having a spring pressed bolt slidable therein, and adapted to engage selected teeth to hold the fence-wire engaging bar in adjusted positions with respect to the head.

5. A jack of the class described comprising a head, a fence-wire engaging bar carried by the head, means carried by the head for shifting the bar relative thereto, a chain connected with the head and adapted to be anchored with the ground to hold the head immovable to permit shifting of said bar, as and for the purpose set forth.

In testimony whereof I affix my signature.
JESSE BECHT. [L. s.]
